UNITED STATES PATENT OFFICE.

WILLIAM J. MURRAY, OF NEW YORK, N. Y.

SCAFFOLD-SUPPORT.

SPECIFICATION forming part of Letters Patent No. 769,395, dated September 6, 1904.

Application filed March 7, 1904. Serial No. 196,895. (No model.)

To all whom it may concern:

Be it known that I, WILLIAM J. MURRAY, a citizen of the United States, residing at New York, in the county of New York and State of New York, have invented certain new and useful Improvements in Scaffold-Supports, of which the following is a specification, such as will enable those skilled in the art to which it appertains to make and use the same.

This invention relates to supports for scaffolds used in the construction of steel or iron frame buildings, and particularly in building or filling in the walls of such buildings after the framework has been completed; and the object of the invention is to provide improved supports for scaffolds of this class and improved means for raising and lowering such scaffolds, and particularly for raising the scaffolds; and with these and other objects in view the invention consists in the construction, combination, and arrangement of parts hereinafter described and claimed.

The invention is fully disclosed in the following specification, of which the accompanying drawings form a part, in which the separate parts of my improvement are designated by suitable reference characters in each of the views, and in which—

Figure 1 is a vertical section on the line 1 1 of Fig. 2; Fig. 2, a front view of a part of the wall of a building provided with my improved scaffold-supports, two of which are shown; Fig. 3, a plan view of one of my improved scaffold-supports; Fig. 4, a side view thereof; Fig. 5, a section on the line 5 5 of Fig. 4; Fig. 6, a section on the line 6 6 of Fig. 3, and Fig. 7 a section on the line 7 7 of Fig. 3.

In the drawings forming part of this specification, reference being made to Figs. 1 and 2 of the drawings, I have shown at *a* a part of one of the walls of a building, said wall being built around and inclosing the usual steel or iron framework composed of horizontally-arranged beams *b* and vertical columns *b*². The framework is also provided with horizontally-arranged beams *b*³, placed at right angles to the beams *b*, and in filling in or building up the wall or walls *a* it is cus-

tomary to provide a scaffold *c*, which must be raised, of course, as the wall is raised or the building thereof progresses.

In the practice of my invention I provide supporting-beams *d*, which in the form of construction shown are placed transversely of the top wall beam or beams *b* and the inner ends of which are connected with supplemental beams *d*², arranged transversely to the beams *b*³ by means of the yokes or other locking devices *d*³, and on the front projecting ends of the beams *d* are placed my improved scaffold-supports *e*. The beams *d* are arranged in pairs, as shown in Fig. 2, and in the construction of the supports *e*, one of which is mounted on each pair of the beams *d*, I provide a frame comprising a base *e*² and side members *e*³ and in the form of construction shown the base *e*² is provided with side flanges *e*⁴, which are secured to the flanges *d*³ of the beams *d* by keepers *d*⁵ or in any desired manner, and the beams *d* in the form of construction shown are U-shaped in cross-section and said beams are so placed that the flanges thereof project outwardly at the top and bottom thereof; but the supports *e* may be connected with the beams *d* in any desired manner, and said beams may be of any preferred form. The base *e*² of the framework of the supports *e* is open, and mounted in the side members *e*³ of said frame or at the tops thereof are two transverse shafts *f* and *g* and a central shaft *h*. The shaft *f* is provided with a drum *f*², which is secured thereto, and the shaft *g* is provided with a drum *g*², which is secured thereto, and the shaft *h* is provided with a small gear-wheel or pinion *h*², which meshes with large gear-wheels *f*³ and *g*³ at the ends of the drums *f*² and *g*² and secured to said drums or to the shafts *f* and *g*. The drums *f*² and *g*² are also provided with cables *f*⁴ and *g*⁴, which are secured thereto, preferably by means of eyes *f*⁵ and *g*⁵, with which said drums are provided, and these cables support the scaffold *c* in the usual manner, being connected therewith at *f*⁶ and *g*⁶.

In the form of construction shown two of the supports *e* are employed; but it will be understood that any desired number of said

supports may be employed, according to the length of the scaffold *c*. One end of the shaft *h* is also provided with a ratchet-wheel *h*³, and mounted on said shaft and free to turn thereon is a lever-arm *i*, having a longitudinal slot or opening *i*², through which the ratchet-wheel *h*³ passes, and said lever-arm is provided at one end of the slot or opening *i*² with a pawl *i*³, which operates in connection with the ratchet *h*³, and said end of said lever-arm is also provided with a weight *i*⁴, and connected with the other end thereof is a cord, rope, or cable *i*⁵, which extends down to the scaffold *c*, and a downward pull on the cords *i*⁵ of each of the supports *e* will result in turning the shaft *h* of each of said supports and in the turning of the drums *f*² and *g*², so as to wind the cables *f*⁴ and *g*⁴ thereon and the consequent raising of the scaffold *c*. At the end of each pull on the cords or ropes *i*⁵ the weight *i*⁴ depresses the rear ends of the lever-arms *i* and raises the front ends thereof, and another pull on the cords or ropes *i*⁵ will result, as above stated, in winding the cables *f*⁴ and *g*⁴ on the drums *f*² and *g*², and this operation may be repeated until the scaffold is raised to the desired point.

The drum *f*² in the form of construction shown is also provided at the end opposite the gear-wheel *f*³ with a ratchet-wheel *j*, and a pawl *j*² operates in connection therewith. The shaft *g*² is provided at the end thereof opposite the gear-wheel *g*³ with a brake-drum *k*, or this drum may be formed on or connected with the drum *g*², and the ratchet-wheel *j* may be formed on or connected with the drum *f*², and pivoted adjacent to the shaft *g* or to the brake-drum *k*² is a lever *m*, and secured to the end of said lever adjacent to said drum is a brake-band *m*², this connection being made at *m*³, and the band *m*² is passed around the brake-drum *d*² and connected with the lever *m* at *m*⁴, and a downward movement of the lever *m* will result in applying the brake-band *m*², so as to regulate the turning of the drum *g*² in the downward movement of the scaffold, when it is desired to lower said scaffold. In this operation of lowering the scaffold the pawl *j*² must be turned backwardly, so that it will not engage the ratchet-wheel *j*, and it will be understood that the lowering of the scaffold must be manipulated from the top of the building or from the supports of the parts *e*, and in this operation the pawl *i*³ must also be turned out of engagement with the ratchet-wheel *h*³. With the form of construction shown the drums *f*² and *g*² are turned in the direction of the arrows *x* in Fig. 4 when raising the scaffold, and when lowering the scaffold said drums are turned in the direction of the arrows *y*, and one side *e*² of the framework of the support or supports *e* is provided with pins or stops *n* and *n*², which limit the movement of the lever-arm *i*.

It will be understood that the supporting-beams *d* may be placed at any desired point, and various changes in and modifications of the construction herein described may be made without departing from the spirit of my invention or sacrificing its advantages, and I reserve the right to make all such alterations therein as fairly come within the scope of the invention.

Having fully described my invention, what I claim as new, and desire to secure by Letters Patent, is—

1. A scaffold-support, comprising a framework, two parallel drums mounted therein, a central shaft mounted between said drums and geared in connection therewith, a lever mounted on one end of said shaft and adapted to turn thereon, a ratchet secured to said shaft adjacent to said lever, a pawl connected with said lever and operating in connection with said ratchet, and means for operating said lever, substantially as shown and described. 85

2. A scaffold-support, comprising a framework, two parallel drums mounted therein, a central shaft mounted between said drums and geared in connection therewith, a lever mounted on one end of said shaft and adapted to turn thereon, a ratchet secured to said shaft adjacent to said lever, a pawl connected with said lever and operating in connection with said ratchet, and means for operating said lever, one of said drums being also provided at the end thereof opposite said lever with a brake, substantially as shown and described. 95

3. A scaffold-support, comprising a framework, two parallel drums mounted therein, a central shaft mounted between said drums and geared in connection therewith, a lever mounted on one end of said shaft and adapted to turn thereon, a ratchet secured to said shaft adjacent to said lever, a pawl connected with said lever and operating in connection with said ratchet, and means for operating said lever, one of said drums being also provided at the end thereof opposite said lever with a brake, and the other with a lock, substantially as shown and described. 100

4. A scaffold-support for steel-frame structures, comprising beams adapted to be connected with the frame so as to project therefrom, a frame adapted to rest on the projecting ends of said beams, two parallel drums mounted in said frame, a central shaft mounted between said drums and geared in connection therewith, means for turning said drums, and means for locking said drums, substantially as shown and described. 115

5. A scaffold-support for steel-frame structures, comprising beams adapted to be connected with the frame so as to project therefrom, a frame adapted to rest on the projecting end of said beams, two parallel drums mounted in said frame, a central shaft mounted between said drums and geared in connection therewith, means for turning said drums, and means for locking said drums, substantially as shown and described. 125

tion therewith, means for turning said drums, means for locking said drums, and cables wound on said drums and adapted to support a scaffold, substantially as shown and described.

In testimony that I claim the foregoing as my invention I have signed my name, in pres-

ence of the subscribing witnesses, this 5th day of March, 1904.

WILLIAM J. MURRAY.
